CLAIM

The ornamental design for a sports shoe, as shown and described.

DESCRIPTION

FIG. 1 is a front elevational view of an ornamental design for a sports shoe showing our new design;

FIG. 2 is a rear elevational view of the sports shoe shown in FIG. 1;

FIG. 3 is a left side elevational view of the sports shoe shown in FIG. 1, the right side view being a mirror image thereof; and,

FIG. 4 is a top plan view of the sports shoe shown in FIG. 1.

The right side of the sports shoe is substantially symmetrical to the left side shown in FIG. 3. The disclosure is showing a left shoe, it being understood that the right shoe is a mirror image thereof. The dash-dot broken lines are included for the purpose of illustrating portions of the sports shoe that form no part of the claimed design.
